UNITED STATES PATENT OFFICE.

HENRY B. RUGGLES, OF PASADENA, CALIFORNIA, ASSIGNOR TO AMERICAN PRODUCTS COMPANY, OF ST. LOUIS, MISSOURI.

BOX.

1,271,948.

Specification of Letters Patent.

Patented July 9, 1918.

Application filed July 8, 1915. Serial No. 38,752.

To all whom it may concern:

Be it known that I, HENRY B. RUGGLES, a citizen of the United States, residing at Pasadena, in the county of Los Angeles and 5 State of California, have invented certain new and useful Improvements in Boxes, of which the following is a specification.

This invention has relation to certain new and useful improvements in boxes, and has 10 for its primary object to provide a box which will be of such construction that the parts thereof may be carried in stock and readily assembled and secured together as the box is packed.

15 The invention has for another object, the provision of a box of this character in which the various parts thereof will be of extremely simple as well as novel construction and which when carried in stock, will 20 occupy but little space.

The invention has for still another object, the provision of a box which will be of such construction that the top and bottom thereof may be placed upon one another, and the 25 body of the box folded to flat and compact form when the parts of the box are separated and stored or carried in stock.

A further object of the invention resides 30 in the provision of a box of this character, which will be of such construction that the bottom and top may be readily and automatically secured to the body of the box as the box is assembled for use.

A still further object of the invention 35 resides in the provision of a box of the above stated character which will be of such construction that the edges of the body sides will automatically catch in locking grooves in the top and bottom of the box to lock said 40 body with said top and bottom with the body of the box automatically as the box is assembled, without the necessity of employing screws or other securing members.

The invention has for a still further object, the provision of a box of this character, which will be of extremely simple construction as well as durable and cheap to manufacture, easily and readily assembled, light in weight, and which will be of such 50 construction that the height or depth of the box may be readily regulated by varying the height or depth of the collapsible body, which, if desired, may be carried in stock in only a large or deep size and cut to form the

bodies of the desired height or depth when 55 assembling the boxes to receive hats, fruits or other objects which may be packed and shipped in boxes of this type.

With these and other objects in view this 60 invention consists in the novel construction, combination and arrangement of parts as will be hereinafter more in detail described and the asserted novelty specifically pointed out in the claims.

In the accompanying drawings which 65 fully and clearly illustrate the invention:—

Figure 1 is a top plan view of a box constructed in accordance with my invention and showing the same in assembled form and with the auxiliary movable top secured 70 in position,

Fig. 2 is a transverse vertical section through the box as shown in Fig. 1,

Fig. 3 is a transverse horizontal section 75 through the same,

Fig. 4 is an enlarged fragmentary detail vertical section through the upper edge of the box, showing clearly the manner in which the parts are secured together.

Fig. 5 is a fragmentary detail bottom 80 plan view of one corner of the top of the box with the side pieces thereof separated to show clearly the construction of the same and the manner in which they fit together to form the corners of the top, and 85

Fig. 6 is a detail elevation of one corner of the bottom of the box with the side pieces thereof separated to show clearly the construction of the same and the manner in which they fit together to form the corners 90 of the bottom of the box.

Referring more particularly to the drawings in which similar reference characters indicate corresponding parts throughout the several views, 1 designates the body of 95 the box which is preferably formed of a fibrous pulp board, but may be formed of cardboard or other suitable material, and is broken at suitable points and bent where broken to form the corners of the body of 100 the box, it being understood that the body is formed preferably of a continuous piece, as clearly shown in Fig. 3.

The body 1 is preferably of such size as to form, when opened up, the body of a box 105 of the desired width with the opposite portions of said body forming the opposite sides of the box body and the height or

depth of the box body will depend upon the height of the body 1 after the lower and upper edges 2 and 3 respectively are broken and bent back to form locking edges to lock upon the body 1 the bottom and top of the box, as will be later clearly and fully described.

The body 1 is preferably carried in stock and is of such size that without being cut, 10 the height of the body will be such that it may be used to form a box of the greatest depth that will be required by the party carrying the stock. This will make it possible to use the same stock for forming or 15 making up boxes of different depths or heights without carrying the stock in more than one size, provided the boxes are to be all of the same shape and width. Of course, for different shape or different width boxes, 20 the stock for the body of each type of box may be carried, but only one size or one height of body stock for each type of box will be required.

The bottom of the box consists of a frame 25 formed of the side frame members 4 and a bottom board 5 secured upon the same inwardly of the longitudinal channels 6 of said side frame members 4. The longitudinal channels 6 of said side frame members 30 4 extend practically the entire length of the upper portions of said side frame members 4 and connect at their ends to form a continuous channel for the lower edge of the body 1, as will be readily understood by referring 35 to the drawings. The channels 6 are also preferably wider at their lower portions than at their upper portions to provide the overhanging locking flanges 7, which may extend over the inner portions of the channels 6, as shown in the drawings, or over 40 the outer portions of said channels, as will be readily understood. It will also be understood that the channels 6 are of the proper depth so that as the broken and bent back 45 lower edges of the sides of the body 1 are pressed against the sides of the body and forced to the bottom of said channels 6, the broken and bent back free edge 2 will move away from the body and to locking position 50 beneath the locking flanges 7, as will be readily understood by referring to Fig. 2 of the drawings.

It will also be readily understood by referring to Figs. 5 and 6 that the side frame 55 members 4 off the bottom of the box are all beveled or cut at an angle at their ends from the upper faces of said members 4 to the bottom of the longitudinal channels 6 there- 60 of in order to form the square corners for the bottom of the box as the ends of said members 4 are brought together. It will also be seen that in order to securely fasten together the side frame members 4, certain of said members 4 have their lower portions 65 cut away at their ends, as shown at 8 in

Figs. 5 and 6, while the remaining side members 4 have their lower portions squared at their ends and cut short of the outer corners of said side members 4, as clearly shown at 9 in Figs. 5 and 6, to fit against the lower portions of the ends of the first mentioned side members 4 as the upper portions of the ends of said first mentioned and second mentioned side members are brought together to form the frame of the bottom of the box. 75

It will further be seen that as the edges of the bottom board 5 are slightly higher than the upper faces of the side frame members 4 of the bottom, and of the upper edge of the channels 6, said edges of the bottom board 5 will assist in guiding the lower edge of the body 1 to proper position above the channels 6, during the operation of securing the body 1 upon the bottom of the box. It will also be readily understood that in order to securely fasten together the body 1 and the bottom of the box and prevent play of the broken and bent back lower edge 2 of the body 1 within the channels 6, any suitable cementing material, indicated by the 80 numeral 10, may be poured into the channels 6 after said broken and bent back lower edge 2 has been forced into said channels 6, thereby making it impossible for the bottom and the body 1 of the box to separate accidentally or owing to strain upon said broken and bent back lower edge 2 during use of the box. It will further be evident that when the cementing material is employed, it will be impossible for unauthorized parties to 85 insert a tool in the channels 6 for the purpose of engaging and withdrawing the broken and bent back lower edge 2 and thereby reaching the contents of the box. 90

After the bottom has been secured upon 105 the body of the box, while the latter is in inverted position, the box is reversed to bring the same in proper position for packing, after which the top may be secured upon the body of the box. 110

In the drawings I have shown the top as consisting of side frame members 11 similar to the side frame members 4 of the bottom and having channels 12 similar to the channels 6 to receive the broken and bent back upper edge 3 of the body 1, and also provided with inwardly directed locking flanges 13 to prevent withdrawal of said broken and bent back upper edge 3. It will also be seen that a suitable cementing material 14 is 120 poured into the channels 12 to prevent play of the broken and bent back edge 3 within said channels 12 and also make it impossible for unauthorized parties to reach and tamper with said broken and bent back edge 3 125 after the same has been inserted in the channels 12 and permitted to move outwardly to position back of the locking flanges 13. It will further be understood that the side frame members 11 of the top are of substan- 130

tially the same construction as the side frame members 4 of the bottom and secured together in a similar manner at their ends.

The side frame members 11 of the top are, 5 however, provided upon their inner sides with lower flanges 15 forming a seat for the inner frame 16 of the main removable portion of the top and to the under face of which inner frame 16 is secured a flat sheet 10 17 of transparent material to expose to view the contents of the box without the necessity of removing the top or in any manner opening the box. The main removable part of the top may be readily secured in position 15 by suitable securing members 18 passed through the sides of the inner frame and into the side frame members 11, as clearly shown in Figs. 1 and 2.

The securing members 18 are also clearly 20 shown in Fig. 4, in which one of said securing members 18 is shown as also passing through the upturned edge 19 of a protecting sheet 20 of cardboard or the like placed over the flat sheet 17 of transparent material 25 to protect the same and also protect the contents of the box from exposure to light when the contents is of such nature that exposure thereof to light would have bad effect upon said contents.

30 It will be understood that the construction of the top as well as other parts of the box may be varied at will, and the top as well as the bottom may be formed in a single section and permanently secured to the body 35 of the box, if desired. It will also be understood that after the box has once been used, the body may be cut around the edge and again broken and bent back to form new locking flanges, thereby providing a new box 40 of decreased height and this operation may be repeated indefinitely. This will be especially desirable when the top is made in one section permanently secured to the body 1 instead of constructing the top in the manner 45 shown in Figs. 1 and 2 and also Fig. 3 of the drawings, with the central portion of said top removable.

While the preferred embodiment of the invention has been shown and described, it 50 will be understood that many minor changes in the details of construction and arrangement of parts may be made within the scope of the appended claims without departing from the spirit of the invention or sacrificing 55 any of the advantages thereof.

What is claimed is:—

1. A box body having an edge folded back upon itself, whereby to form a downwardly depending lip, and a rigid top mem-

ber having a locking channel formed therein, 60 adapted to have said folded edge inserted bodily thereinto, with means therein for automatically interlocking with said downwardly depending lip when it is attempted to remove said top member. 65

2. A box body having its top and bottom edges folded back upon said body there-around, whereby to form downwardly and upwardly projecting lips, top and bottom members having formed therein locking 70 channels adapted to have said folded edges inserted bodily thereinto, and means in said channels adapted to automatically interlock with said lip members when it is attempted to remove said top and bottom 75 members.

3. A box comprising a body having its upper and lower edges broken and bent back, a bottom including a frame provided with a continuous locking channel having an over-hanging flange on its open side, one of the edges of the body being engaged in said locking channel and beneath said over-hanging flange to lock together said body and said bottom, and a top locked upon the upper edge of said body. 80

4. A box comprising a body, a bottom locked upon one edge of said body, the remaining edge of said body being broken and bent, and a top having a locking channel 90 provided with an overhanging flange closing a portion of its open side, the said remaining edge of the body being secured in said locking channel.

5. A box body having an edge folded upon 95 itself, whereby to form an acute angle around said edge, a cover frame having an interlocking channel formed therein and adapted to have said folded edge inserted bodily thereinto, means in said channel for 100 automatically interlocking with said folded edge, when it is attempted to remove said cover frame, and a cover member secured in said cover frame.

6. A box body having an edge folded upon itself, whereby to form an acute angle around said edge, a cover frame having an interlocking channel formed therein and adapted to have said folded edge inserted thereinto, means in said channel for automatically interlocking said folded edge, when it is attempted to remove said cover frame, said cover frame having an inwardly projecting flange, and a cover member seated in said cover frame upon said flange, sub- 110 stantially as described. 115

In testimony whereof I affix my signature.
HENRY B. RUGGLES.
